SPECTACLE TEMPLE

Austin B. Belgard, Evanston, Ill.

Application October 29, 1954, Serial No. 32,870

Term of patent 14 years

(Cl. D57—1)

Fig. 1

Fig. 2

Fig. 3

Fig. 4

Fig. 5

Fig. 1 is a top plan view of a spectacle temple showing my new design;

Fig. 2 is an inner side view in elevation;

Fig. 3 is an outer side view in elevation;

Fig. 4 is a front elevational view thereof; and

Fig. 5 is a rear elevational view thereof.

I claim:

The ornamental design for a spectacle temple, as shown.
